US00D328954S

United States Patent [19]

Brech

[11] Patent Number: Des. 328,954

[45] Date of Patent: ** Aug. 25, 1992

[54] DIAGNOSTIC ASSAY ROBOTIC MACHINE

[75] Inventor: James M. Brech, San Clemente, Calif.

[73] Assignee: MicroProbe Corporation, Bothell, Wash.

[**] Term: 14 Years

[21] Appl. No.: 522,431

[22] Filed: May 11, 1990

[52] U.S. Cl. D24/186; D24/216

[58] Field of Search D24/216, 231, 232, 186; 422/62, 63, 64, 68, 101

[57] CLAIM

The ornamental design for a diagnostic assay robotic machine, as shown and described.

DESCRIPTION

FIG. 1 is a perspective view of a diagnostic assay robotic machine showing my new design;

FIG. 2 is a top plan view thereof;

FIG. 3 is a front elevational view thereof;

FIG. 4 is a right side elevational view thereof, the left side elevational view being a mirror image thereof;

FIG. 5 is a rear elevational view thereof; and,

FIG. 6 is a bottom plan view thereof.

*FIG. 1.**FIG. 2.*

FIG. 3.

FIG. 4.

FIG. 5.

FIG.-6.
